LAMP HEAD FOR A BARRICADE FLASHER SIGNAL UNIT

Sidney A. Heenan, Park Ridge, Ill., assignor to Elastic
Stop Nut Corporation, Union, N.J., a corporation of
New Jersey

Filed Mar. 13, 1964, Ser. No. 78,989

Term of patent 14 years

(Cl. D48--24)

FIG. 1 is a perspective view of a lamp head for a barricade flasher signal unit embodying my new design;
FIG. 2 is a side elevation thereof; and

FIG. 3 is a front elevation thereof.

The dominant features of this design reside in portions shown in full lines on the drawing.

I claim:

The ornamental design for a lamp head for a barricade flasher signal unit, as shown and described.
